UNITED STATES PATENT OFFICE.

CHARLES S. BURTON, OF OAK PARK, ILLINOIS.

CONTAINER FOR MUSIC-ROLLS AND THE LIKE.

1,388,093.

Specification of Letters Patent. Patented Aug. 16, 1921.

Application filed September 15, 1919. Serial No. 323,828.

To all whom it may concern:

Be it known that I, CHARLES S. BURTON, a citizen of the United States, and a resident of Oak Park, in the county of Cook and 5 State of Illinois, have invented certain new and useful Improvements in Containers for Music-Rolls and the like, of which the following is a specification, reference being had to the accompanying drawings, forming a 10 part thereof.

The purpose of this invention is to provide an improved container, particularly adapted for such articles as music rolls and the like, of which the containers are commonly 15 stacked in piles or tiers with the ends only accessible, so that it is desirable to have the contents withdrawable through the end of the container. It consists in the elements and features of construction shown and 20 described, as indicated in the claims.

In the drawings:

Figure 1 is a longitudinal vertical section of a container embodying this invention, the same being shown in closed position with a roll therein.

Fig. 2 is a similar view showing the container closure withdrawn for protruding the end of the roll to permit its engagement by the hand for complete withdrawal.

The structure shown in the drawings comprises a tubular box 1, having one end open and provided with a telescoping open top box member, adapted to contain the rolls or other articles for which the box is designed, 30 said interior open-top member, 2, having its outer end portion 2^a, separated from the remainder and hinged thereto at the bottom so that it may swing down out of the way of the out-coming roll when the latter is to be 35 withdrawn as seen in Fig. 2. Desirably for convenience of the operation of the locking device hereinafter more particularly described, the division to separate the down-swinging end portion 2^a, of the member, 2, 40 from the main body of said member, 2 is made an oblique cut as shown in Fig. 2, so that the down-swinging member has its upper edges 2^b, sloping down inwardly. And it is also desirable for the same reason that 45 the separate ends of the main body of said interior member shall be cut off obliquely in the opposite direction to form edges 2^c, sloping upward inwardly as also seen in Fig. 2. It is also desirable for the same general purpose that the said upper edges of 50 the main body of the member, 2, are notched just behind said last mentioned upward inward sloping edges, said notches, 2^d, having abrupt shoulders facing outwardly and having the other side sloping inwardly, for engagement of the latch device hereinafter described.

Said latch device consists of a three-sided open-ended parallelogram made of wire bent in the form indicated, and with two side 60 arms, 4, 4, adapted to extend between the inner and outer box members, 1 and 2, the free ends of said latch member being pivoted to the two opposite vertical sides of the outer member, 1, and preferably constructed 65 so as to cause the cross bar, 4^a, connecting the two side arms, to be spring pressed downward at its lodgment on the upper edges of the main box member, 2, and for engagement with the notches, 2^d, mentioned as the 70 withdrawn position of this box member shown in Fig. 2. This spring action of the latch may be obtained by bending the side bars, 4, upward between their pivoted ends and the cross bar, 4^a, to cause them to collide 75 with the top of the outer member, 1, before the cross bar clears the end of the closure member, 2^a, so that further upward movement for releasing said closure member is possible only by springing said side arms, 4. 80 This latch member is adapted to swing down 85 in front of the inner telescoped member when the latter is in closed position, the cross bar, 4^a, extending across the forward end of said inner telescoped member and 90 thereby locking said member in closed position. For convenience of disengaging the latch, 4, from its said locked position to permit withdrawal of the interior member, 2, 95 there is hinged to the upper edge of the forward end of the hinged and down-swinging portion 2^a, of said member, 2, a stiff-flap 5, preferably of the area substantially of said forward end so as to cover the same when hanging down normally. The latch, it will 100 be understood, engages in front of this stiff flap latch-release member, 5, in locking the interior member, 2, in closed relation. The lower or free edge of said flap or release member, 5, is provided with a lug, 5^b, for 105 convenience of engaging it in opening the box. The operator seizing this lug and swinging the release member, 5, upward will cause the latch cross bar, 4^a, to slide 110 upward along said release member and slip over the edge of the hinged and down-wardly-swinging portion, 2^a, of the interior

box member, 2. The operator pulling normally on the lug as will be done for swinging up the release member, will also pull outwardly upon the box member and withdraw 5 draw said interior member as soon as the latch has been swung up over the upper edge of it so as to release it for such result. The latch having run back over the end of the said member, 2^a, will drop by gravity 10 or by the spring action above referred to onto the downwardly-sloping rear edges of the sides of said member, 2^a, not so far as to pass below the forward angular corners, 2^f, of the main box member upon the other side 15 of the main box member, 2; and as the operator continues to withdraw said member, 2, the latch bar will slide up on the sloping forward edges 2^e, of the main box member and drop into notches, 2^b, and stop the withdrawing movement by the engagement of the cross bar with the abrupt rear shoulders of said notches, the operator releasing the member, 2^a, will drop to descending position as shown in Fig. 2, the roll will be 20 found protruding a substantial distance to which the inner member has been withdrawn by the operator, and may be taken hold of and completely withdrawn.

In replacing the roll, the end of the spool 30 will be readily inserted under the end of the cross bar, 4^a, of the latch and thrust in until the rear end strikes the rear end of the interior member, 2, when the operator taking hold of the lug and lifting the detached and 35 down-swinging portion, 2^a, to horizontal position will thrust in the entire member, 2, carrying the roll with it into position at which the latch will spring down in front of the hinged portion, 2^b, of the inner telescoped member, and secure it in closed position.

I claim:—

1. A container consisting of an outer tubular box member having an open end; an 45 interior open-top box member adapted to telescope longitudinally in the tubular box member, said open-top member having an outer end portion severed from the remainder and hinged thereto at one side for 50 folding away from the remainder to leave said remainder open ended; a latch pivoted to the tubular box member for swinging to engage the severed and hinged end portion in the same planes in which said severed 55 end portion swings for opening; and means on the severed and hinged portion for partly withdrawing the interior box member from the exterior member.

2. In the construction defined in claim 1, 60 a lug hinged at the edge of the end wall of the severed and hinged part over which the latch swings for locking engagement, said lug adapted to be engaged by the latch when the latter is engaged with said end for locking; whereby pull on the lug first disen-

gages the latch and then pulls out the interior member.

3. In the construction defined in claim 1, a stiff lug substantially of the area of the box-end hinged at the edge of the end wall 70 of the severed and hinged part over which the latch swings for locking engagement, and adapted to be engaged by the latch when it engages said end for locking, whereby the swinging of the lug about its hinge 75 first disengages the latch, and continued pull on the lug withdraws the interior member.

4. In a construction defined in claim 1, the latch being a three-sided or open-ended 80 parallelogram having the two parallel sides extending along two opposite sides of the outer locked member and its ends pivoted thereto, and having the third intermediate side adapted to extend across the front of the outer end of the severed and hinged part 85 of the inner member for locking engagement to hold said inner member at in-thrust position in the outer member.

5. In the construction defined in claim 1, 90 the latch being a three-sided or open-ended parallelogram having the two parallel sides adapted to extend inside the exterior member and pivoted at their ends to the opposite side walls thereof; a third or intermediate 95 side being adapted to extend across the outer end of the interior member at in-thrust position of said member.

6. In the construction defined in claim 1, the latch piece formed and attached for 100 spring action tending to swing it to and hold it yieldingly at locking position.

7. In the construction defined in claim 1, the latch being a three-sided, open-ended 105 parallelogram having its opposite parallel sides extending along opposite sides of the box member, and its third or intermediate side extending across the open end for engaging the interior member at its inserted 110 position, the severed and hinged portion of said interior member having side walls whose edges which are exposed toward the intermediate side of the latch when the interior member is at withdrawn position are sloped for lifting the latch over the end of 115 said engaged member in the in-thrusting or closing movement of the interior member.

8. In the construction defined in claim 1, the latch being a three-sided, open-ended 120 parallelogram having its opposite parallel sides extending along opposite sides of the box member, and its third or intermediate side extending across the open end of the box for engaging the interior member at closed position, said interior member having side walls of which the edges are exposed to the latch at open position, and are sloped for lifting the latch in the withdrawing movement of said interior member.

9. In the construction defined in claim 1, 130

the latch being a three-sided, open-ended parallelogram, having its opposite parallel sides extending along opposite sides of the box and its third or intermediate side extending across the open end of the box for engaging the head or end of said interior member at closed position, said interior member having side walls of which the edges which are exposed to the latch at open position are sloped for lifting the latch in

the withdrawing movement of said interior member, and an outwardly-facing stop shoulder positioned inwardly beyond said sloping edge for engaging the middle member of the latch to arrest the withdrawing movement of the interior member.

In testimony whereof, I have hereunto set my hand at Chicago, Illinois, this 12th day of September, 1919.

CHARLES S. BURTON.
